United States Patent Office

Des. 194,751
Patented Mar. 5, 1963

194,751

CHEST OR SIMILAR ARTICLE

Donald E. Green, 11629 Montana Ave.,
Los Angeles, Calif.

Filed Nov. 14, 1960, Ser. No. 62,811

Term of patent 14 years

(Cl. D33—19)

Fig. 1.

Fig. 2.

Fig. 3.

FIG. 1 is an elevational front view of a chest or similar article showing my design;

FIG. 2 is an elevational side view thereof; and

FIG. 3 is a perspective front view thereof.

The back of the cabinet is plain and unornamented.

I claim:

The ornamental design for a chest or similar article, as shown and described.
